Patented Dec. 21, 1915.

UNITED STATES PATENT OFFICE.

WILLIAM N. BAUER, OF CINCINNATI, OHIO, ASSIGNOR OF ONE-HALF TO ALBERT C. KAUFMANN, OF CINCINNATI, OHIO.

GUIDE FOR TROLLEYS FOR TROLLEY-WHEELS OF OVERHEAD TROLLEYS FOR ELECTRIC CARS.

1,165,309.

Specification of Letters Patent.

Patented Dec. 21, 1915.

Application filed March 13, 1914. Serial No. 824,389.

To all whom it may concern:

Be it known that I, WILLIAM N. BAUER, a citizen of the United States, and a resident of the city of Cincinnati, in the county of 5 Hamilton and State of Ohio, have invented certain new and useful Improvements in Guides for Trolleys for Trolley-Wheels of Overhead Trolleys for Electric Cars, of which the following is a full, clear, and exact 10 description, reference being had to the accompanying drawings, forming part of this specification.

The purpose of my invention is to provide an attachment for the trolley poles used in 15 making connection with the overhead trolley which will enable the operator to readily find the trolley wire and to guide the trolley wheel thereto whenever for any reason the wheels have to be shifted from one line to 20 another or the trolley wheel has become accidentally displaced from the wire.

My object is to furnish a construction which consists of a minimum number of parts, which can be readily and easily attached to the trolley pole and which shall be 25 so constructed as not to interfere in any way with the ordinary use of the trolley pole, and in the event of accidental dislodgment of the pole will tend to ward off the overhead structure and prevent the breaking or tearing of 30 the wire supports.

The invention consists of that certain novel construction and arrangement of parts to be hereinafter particularly pointed out 35 and claimed whereby the above results are attained.

In the drawings, Figure 1 is a side elevation of my invention showing the trolley wheel on the wire. Fig. 2 is a top plan view 40 of the same. Fig. 3 is a side elevation with the trolley guide in use. Fig. 4 is a detail perspective showing the attachment of the pulling rope to the guide. Fig. 5 is a front view of the clamp for securing the guide to 45 the trolley pole.

The trolley guide comprises a bar 1, with projecting forks 2, 2, at one end, and at the other end 3 a means for securing the pulling rope 4 to the guide. The guide bar 1 is pivotally mounted by the bolt 5 to the plate 6 shaped on its opposite end 7 to engage the trolley pole 8, and forming with the corresponding plate 9 similarly shaped at 10 a pair of clamp plates for securely clamping

the device in proper position near the end 55 of the trolley pole, a bolt 11 being employed to draw the two plates together. The clamp plates 6 and 9 do not completely encircle the trolley pole, but they are cut away and curved so as to leave the upper side of the 60 pole 12 free from any projecting portion of the clamp members so that in the event of the trolley wheel 13, which normally rides underneath the trolley wire 14 being accidentally dislodged, no obstruction will be 65 formed to catch or injure the wire supports.

For attaching the trolley rope to the guide bar, I have found that a very perfect means for quickly attaching the pulling rope is to provide two holes in the end of the guide 70 bar and push the end of the pulling rope up through one of these holes and down through the other, as shown in Fig. 4.

The forks 2, 2, of the guide are curved rearwardly and flare outwardly as shown in 75 the drawings, and the shank portion immediately below the forks is curved as shown at 15 to fit within the groove 16 of the trolley wheel, when the bifurcated guide is raised by drawing down on the pulling rope. 80

Normally when the trolley is riding underneath the trolley wire in the usual way, the bifurcated end of the guide drops down as shown in Fig. 1, with the forks below the wire. Should the wheel become accidentally 85 dislodged, or should the operator desire to change the trolley wheel from one wire to another, he draws down upon the pulling rope 4 which at once raises the bifurcated end of the trolley guide and brings the 90 curved portion 15 within the groove in the wheel, so that for the time being, the groove of the wheel is, as it were, extended upwardly and flared outwardly to the extent of the opening between the forks 2, 2. The 95 guide, therefore, gives ample space for the operator to allow the wheel and its guide to be easily brought underneath the wire and embrace the wire between the forks. Then allowing the pole to rise, the trolley 100 wheel is guided directly to the wire. The construction under which the guide bar is arranged to enter the groove of the trolley wheel insures the proper position for the forks, and the wheel will be accurately 105 guided to the wire.

The advantages of my construction will be evident from the foregoing description.

The entire device is made up of only three parts, the bifurcated guide arm and the clamp plates by which it is secured to the trolley pole together with the two bolts. 5 The clamping is accomplished by tightening the single bolt 11 and a shoulder 18 is provided for the plate 9, which acts as a fulcrum to bring the requisite pressure to bear upon the trolley pole and to prevent any 10 binding on the bolt 5 which acts as the pivot pin for the guide. The bolt 11 is provided with an elongated head 17 to prevent turning as the bolt nut on the other end is tightened. The guiding rope does not have to be 15 tied or knotted to secure it to the guide. By simply passing the end of the rope up through one hole and down through the other, I have a perfect lock.

Having thus described my invention, what

I claim as new and desire to secure by Letters Patent, is:—

In combination with a trolley pole and trolley wheel mounted thereon, a guide for said trolley wheel, comprising a shank portion of a width and properly curved to fit 25 in and lie in the groove of the trolley wheel, with flaring upwardly extending prongs at the end of the shank portion located so as to flare out and up from the trolley wheel groove when the shank portion is in place 30 with the angle of the said prongs registering with the slot of the wheel, and adjustable, detachable means for pivotally mounting the shank portion on the trolley pole.

WILLIAM N. BAUER.
